UNITED STATES PATENT OFFICE

JOSEPH B. ENNIS, OF PATERSON, NEW JERSEY

LOCOMOTIVE BED

Application filed February 28, 1929. Serial No. 342,911.

The invention relates to locomotives having boiler-supporting frame or bed side members, provided with a plurality of journal box openings, and more particularly to a sectional frame or bed having a front section or portion formed as an integral structure.

A locomotive frame or bed of integral formation possesses a high degree of strength, rigidity and durability in proportion to its weight, with an attendant material increase in the factor of safety, and effects a substantial economy in maintenance cost.

Heretofore, when an integral frame or bed has been employed in the above type of locomotive, it has been made to extend throughout at least the entire length of the side members including the journal box openings, or has been made to include only a portion thereof in advance of the main drive. With regard to the present invention, it has been discovered that the principal advantages of a locomotive integral frame or bed may be attained, if that portion only of the frame or bed be made as an integral structure that includes the section wherein all or substantially all of the "working" of the side frame members, cross ties, and associated parts take place, which has been found to be substantially comprised in that part of the frame or bed extending from the main axle forward, and if this is formed in a rigid one piece casting without any bolts or other fastening, there is no difficulty whatever in maintaining a built-up construction back of the main axle.

The present invention therefore, contemplates making the side members of a locomotive frame or bed in sections, by dividing them at a suitable point to the rear of the main journal box openings, and forming the front portions and cross members as an integral structure. The most suitable point of division has been found to be to the rear of the main journal box openings, between these openings and the adjacent openings to the rear thereof. In the present embodiment, as shown in the drawings, the division is taken between the second and third pairs of box openings, the second pair of openings, in this particular type of locomotive, being the main journal openings. An integral

partial frame is thus provided which includes, as an integral casting unit, those parts wherein substantially all of the undesirable "working" of parts usually take place. Such a structure is found to have substantially all the advantages of an all integral bed or frame. There is no material difference in maintenance, while on the other hand, there is a material saving in the cost of manufacture. Furthermore the integral portion, in the present improved construction, being relatively small, is more easily machined and more readily applied. Moreover it is more readily replaced and with less cost if occasion requires, and likewise the portions to the rear may be replaced without in any way disturbing or necessitating the replacement of the forward integral section. While it has been stated that the side members are preferably divided between the main journal opening and the journal opening to the rear thereof, it is obvious that the integral portion may be extended somewhat rearwardly without departing from the spirit of the invention, for, while the greatest advantage is believed to be in the provision of an integral frame portion made no longer than is necessary to attain the desired ends, obviously much of the benefits will be attained even though the integral portion be somewhat longer.

The invention as thus set forth, being borne in mind, it further contemplates the addition, as part of the integral structure, of one or more of the features usually associated with the forward portion of a locomotive bed, as, for instance, the bumper, or bumper seat, the saddle, cylinders, and boiler guide bearing seat. Furthermore, the rear portion of the frame, which is suitably formed for rigid fastening to the forward integral portion, may also be made integral, or may be of composite structure, or may be a combination of both, and may also be made integrally with one or more of the features usually associated with this portion of the bed.

The improvement claimed is hereinafter fully set forth.

In the accompanying drawings: Figure 1 is a diagrammatic side view of a locomotive embodying the invention, Fig. 2, a side view

enlarged of a fragment of the frame or bed sections of Fig. 1 including the joint, Fig. 3, a transverse section of the joint taken on the line 3—3 of Fig. 4, Fig. 4, a view in perspective of an entire locomotive frame or bed comprised of two integral sections rigidly connected with the cylinders and various other parts integrally formed on the front section or unit, Fig. 5, a fragmental view similar to Fig. 4, showing the cylinders attached, Fig. 6, a view similar to Fig. 5, the forward end of the front unit being modified to provide for the attachment of the cylinders and saddle, Fig. 7, a view similar to Fig. 4, showing a modification, Fig. 8, a fragmentary plan view including another type of joint for rigidly connecting the frame or bed sections, Fig. 9, a side view of Fig. 8, and; Fig. 10, a transverse section on the line 10—10 of Fig. 8.

In the practice of the invention, referring descriptively to the specific embodiment thereof which is herein exemplified in a locomotive of the type set forth, wherein is shown diagrammatically, such parts only as are deemed necessary for a clear understanding of the invention, the boiler structure A, is supported on a frame or bed B, in any usual or preferred manner. At the forward end of the locomotive is the usual bumper C, and the cylinder saddle, D, from which is disposed on each side of the boiler the cylinders, E, and the attendant driving gear denoted generally by the reference F. The locomotive is shown of a type having four pairs of driving wheels indicated by the reference, G, a four wheel forward truck, H, and a two wheel trailing truck, I.

Considering now that part of the locomotive frame or bed structure which has more directly to do with the present invention, the forward frame unit or section, B1, in each of the views of the drawings is shown as formed of an integral casting preferably of steel. The rear unit B2, is shown in most of the views as an integral casting, but this unit may, with satisfactory results attendant, be made as a built up structure, or even a combined integral and built up structure, as exemplified in Fig. 7 of the drawings.

Referring particularly to Figs. 1-4, the integral front portion B1 of the frame or bed, comprises the two side members, 10, provided with the journal box pedestals, 10a, 10b, two pair being shown, the second pair, 10b, being the main pedestals for the main drive of the locomotive as clearly shown in Fig. 1. The side members are of double wall construction, closed about the pedestals, and at top and bottom, but have large openings, 10c, between the pedestals to lighten the structure. The side members are connected across their top faces by a top plate or web, 10d, which is provided with the openings, 10e, to lighten the structure, and with the openings, 10f, and

10g, for permitting the spring hangers and spring saddles, (not shown), to respectively extend therethrough.

The forward end of the integral frame structure is extended beyond the first pair of pedestals, 10a, and at the forward ends of the extended side members is provided a bumper seat, 11, to which the bumper C is attached, or if desired the seat may be omitted and the bumper made part of the integral structure. To the rear of the bumper seat is the cylinder saddle, D, a transverse vertical strengthening plate, 12, at the front of the saddle, a substantially horizontal transverse strengthening plate, 13, at the rear of the saddle, a guide bearer seat, 14, to the rear of the plate, and cylinders, E, at either side of the saddle, all integrally formed as a unitary casting, with the integral frame section as already described.

While the above features are described as forming part of the integral structure, it will be understood that some of these parts may be made integrally with the frame section, and others associated therewith by bolts or other fastenings as the exigencies of each case will dictate. For instance, Fig. 5, shows the forward integral structure as being formed with side members having portions, 10h, adapted for receiving the cylinders, E1, which are secured thereto by fastenings, 15. The type of locomotive shown in Fig. 5, further includes a strengthening web, 16, having an orifice, 16a, to lighten the structure. Fig. 6 shows the forward end of the integral portion of the frame or bed, instead of being formed with an integral saddle and cylinders, as being formed with a transverse plate or web, 17, connecting the extended side members, provided with openings, 17a, to lighten the structure, and a depressed shouldered portion, 18, serving as a cylinder saddle seat, all of which are integrally formed with the pedestaled portion of the integral structure as a unitary casting.

The casting as shown in Figs. 1 to 7 inclusive, terminates at the rear in an end portion, 19, which forms one member of the joint connecting the two sections of the frame. The other portion, 20, of the joint is formed on the forward end of the rear section of the frame, which is shown in Figs. 2 to 6 inclusive, as being similar in general design to the forward section of the frame, and comprises briefly the rear portions, 21 of the side members, provided with the pedestals, 21a, the side members being connected together across their top faces by a plate or web, 21b, provided with the orifices, 21c, for permitting the spring hangers, and spring saddles (not shown) to extend therethrough. At the rear of the pedestaled portion of the rear frame portion the side members are extended to provide a cradle, 22, which has extended from each side, a bracket, 23, to serve

as a furnace bearer seat, and at the rear end a transverse plate, 24, in which is formed the draw bar pocket, 25.

Fig. 7, shows rear portions, 26, of the side members without the connecting web or plate at the top, and these side member portions, while they may be integral with the cradle, are so constructed that they are separately formed and bolted or otherwise secured to 10 the cradle as shown.

Referring now to the joint connecting the forward and rear sections of the bed, the rear portions of the side members, 10, terminate in upper and lower supporting brackets 19a, 15 19b, respectively, having bevelled upper supporting faces inclined rearwardly. The upper brackets are connected by a similarly inclined plate or web, 19c, it being a continuation of the plate or web, 10d, and the brackets 20 on either side of the frame are connected on their inner sides by the respective orificed vertical plates, 19d, which extend upwardly beyond the plate, 19c, to form supporting flanges, 19e. The other portion, 20, of the 25 joint, comprises upper and lower extensions, 20a and 20b, of the side members, 21, having lower bevelled faces engaging respectively the corresponding bevelled faces of the upper and lower supporting brackets, 19a and 19b, 30 the inner vertical faces of the extensions engaging respectively the flanges, 19e, and vertical plates, 19d. The engaging parts are secured together by means of a plurality of vertical bolts, 27, and the extensions, 20a and 35 20b, are further bolted to the flanges, 19e, and plates, 19d, by means of the horizontal bolts, 28. The respective inclined faces, forming the joint have mating grooves, 29, in which may be inserted keys for tightening the joint 40 in a well-known manner. As will be readily seen the joint thus described is of simple and durable construction, and the parts forming it are easily assembled.

Figs. 8 to 10, show a different form of joint.

45 In this type of joint the rear end of the casting, B1, is formed with a vertical transverse plate, 10i, the side members being extended beyond the plate to form flanges, 10j, having their ends directed inwardly to provide 50 grooves, 10k. The rear portion, 21, of the frame is provided with a forwardly extending restricted portion, 21g, which fits between the flanges, 10j, and is provided with outwardly 55 extending lateral flanges, 21h, which engage the grooves, 10k, the parts being so formed and proportioned as to leave vertical key ways for reception of the keys 30, which are driven tight to hold the parts securely in place, and further secured, by means of the 60 bolts, 31, to the engaging portions of the frame sections for securely holding the parts together. Likewise the plate, 10i, is secured to the front wall of the restricted portion, 21g, by means of the bolts, 32, thereby making a rigid and strong joint connecting the

two portions or sections of the bed together. It will be obvious that in assembling the joint shown in Figs. 8 to 10, one section, as for instance, the section, 21, must be lowered into engagement with the other section, in order 70 to make the connection forming the joint, whereas in the joint shown in Figs. 1 to 7, all that is necessary is to move the members together in a longitudinal direction until the engaging parts are in suitable relation to form 75 the joint whereupon the fastenings are applied. Moreover, such a joint is especially suitable when the rear portions of the side members are made separate, and assembled as a built up section. While two forms of joints have been shown and described, it will be understood that other forms may be devised at will, as the particular type of joint employed, forms no part of the present invention, considered from its broad aspect. 80

The invention claimed and desired to be secured by Letters Patent is:—

1. A boiler-supporting sectional frame having a plurality of pairs of pedestals for journal boxes, comprising a frame section including a part having the pedestals for the journals of the main drive, and a part in advance thereof, formed as an integral casting; portions integral with said section extending rearwardly of said pedestals, formed with bevelled joint faces; an adjacent frame portion to the rear of said section formed with portions extending forwardly and having bevelled joint faces for engaging said faces of the rearwardly extending portions; and means for rigidly securing the rearwardly and forwardly extending portions rigidly together. 95

2. A boiler-supporting sectional frame having a plurality of pairs of pedestals for journal boxes, comprising an integral casting including side members of substantially channel-shaped cross-section, disposed to form pedestals and longitudinal braces, a substantially continuous web connecting the side members, apertured for spring hangers and spring saddles, and having cross-ties, a guide bearer seat, a cylinder saddle, a bumper seat, and a joint portion extending rearwardly of the pedestals; and an adjacent frame portion to the rear of said integral casting, having pedestals for journal boxes, cross-ties, a draw bar pocket, and a joint portion extending forwardly; and means for rigidly securing the joint portions together. 115

3. In a locomotive the combination of a pair of cylinders having pistons; a pair of main drive wheels; main drive rods connecting the pistons and main drive wheels; a pair of drive wheels in advance of the main drive wheels; and a sectional bed comprising, as one of the sections an integral casting extending forwardly from a point at the rear of the main drive wheel axles to a point forward of the cylinders, having side frame 125 130

members and a cross-tie member, each of said side frame members having a pedestal jaw opposite each of the adjacent drive wheels, a separate section comprising the remainder of the bed, and means for securing the casting and the remainder of the bed together.

4. In a locomotive the combination of a pair of cylinders having pistons; a pair of main drive wheels; main drive rods connecting the pistons and the main drive wheels; a pair of drive wheels in advance of the main drive wheels; a pair of drive wheels to the rear of the main drive wheels; and a sectional bed comprising, as one of the sections an integral casting extending forwardly from a point between the main drive wheel axle and the drive wheel axle to the rear to a point forward of the cylinders, having side frame members and a cross-tie member, each of said side frame members having a pedestal jaw opposite each of the adjacent drive wheels, a separate section comprising the remainder of the bed; and means for securing the casting and the remainder of the bed together.

5. In a locomotive the combination of a pair of cylinders having pistons; a pair of main drive wheels; main drive rods connecting the pistons and the main drive wheels; a pair of drive wheels in advance of the main drive wheels; and a sectional bed comprising, as one of the sections an integral casting extending from a point at the rear of the main drive wheels to a point forward of the cylinders, having side frame members, provided each with a pedestal jaw opposite each of the adjacent drive wheels, a cross-tie member, and a cylinder saddle, a separate section comprising the remainder of the bed; and means for securing the casting and the remainder of the bed together.

6. In a locomotive the combination of a pair of main drive wheels; main drive rods connected to said drive wheels; a pair of drive wheels in advance of the main drive wheels; and a sectional bed comprising, as one of its sections an integral casting extending forwardly from a point at the rear of the main drive wheel axle forward of the axle of the drive wheels in advance, including side frame members, having each a pedestal jaw opposite each of the adjacent drive wheels, a cross-tie member, a cylinder saddle, a pair of power cylinders, and pistons in the cylinders connected to the main drive rods, a separate section comprising the remainder of the bed, and means for securing the casting and the remainder of the bed together.

7. In a locomotive the combination of a pair of cylinders having pistons; a pair of main drive wheels; main drive rods connecting the pistons and the main drive wheels; a pair of drive wheels in advance of the main drive wheels; and a sectional bed comprising,

as one of the sections, an integral casting extending forwardly from a point at the rear of the main drive wheel axle to a point forward of the cylinders, having side members, each of said side members having a pedestal jaw opposite each of the adjacent drive wheels, a transverse, substantially vertical member forming a guide bearer seat in advance of said drive wheels, a separate section comprising the remainder of the bed, and means for securing the casting and the remainder of the bed together.

8. In a locomotive the combination of a pair of cylinders having pistons; a pair of main drive wheels; main drive rods connecting the pistons and the main drive wheels; a pair of drive wheels in advance of the main drive wheels; and a sectional bed comprising, as one of the sections an integral casting extending forwardly from a point at the rear of the main drive wheel axle to a point forward of the cylinders having side members, provided each with a pedestal jaw opposite each of the adjacent drive wheels, and a forwardly extending portion providing a bumper seat at the front end of said casting, a separate section comprising the remainder of the bed, and means for securing the casting and the remainder of the bed together.

9. In a locomotive the combination of a pair of cylinders having pistons; a pair of main drive wheels; main drive rods connecting the pistons and the main drive wheels; a pair of drive wheels in advance of the main drive wheels; and a sectional bed comprising, as one of the sections an integral casting extending forwardly from a point at the rear of the main drive wheel axle to a point forward of the cylinders, having side members, provided each with a pedestal jaw opposite each of the adjacent drive wheels, and a forwardly extending portion providing a bumper at the front end of said casting, a separate section comprising the remainder of the bed, and means for securing the casting and the remainder of the bed together.

10. In a locomotive the combination of a pair of cylinders having pistons; a pair of main drive wheels; main drive rods connecting the pistons and the main drive wheels; a pair of drive wheels in advance of the main drive wheels; and a sectional bed comprising, as one of the sections an integral casting extending forwardly from a point at the rear of the main drive wheel axle to a point forward of the cylinders, having side members, provided each with a pedestal jaw opposite each of the adjacent drive wheels, and a separate section comprising the remainder of the bed, said separate section being formed as an integral casting, and means for securing the sections together.

11. In a locomotive the combination of a pair of cylinders having pistons; a pair of main drive wheels; main drive rods connect-

ing the pistons and the main drive wheels; a pair of drive wheels in advance of the main drive wheels; and a sectional bed comprising, as one of the sections an integral casting 5 extending forwardly from a point at the rear of the main drive wheel axle to a point forward of the cylinders having side members, provided each with a pedestal jaw opposite each of the adjacent drive wheels, a separate 10 section comprising the remainder of the bed, said separate section being formed as an integral casting and having side members provided with pedestal jaws and extending rearwardly of the pedestal jaws providing a 15 cradle, and means for securing the castings together.

12. In a locomotive the combination of a pair of cylinders having pistons; a pair of main drive wheels; main drive rods connecting the pistons and the main drive wheels; a pair of drive wheels in advance of the main drive wheels; and a sectional bed comprising, as one of the sections an integral casting 20 extending forwardly from a point at the rear of the main drive wheel axle to a point forward of the cylinders, having side members, provided each with a pedestal jaw opposite each of the adjacent drive wheels, a separate section comprising the remainder 25 of the bed, said separate section being formed as an integral casting and having side members forming a cradle, and brackets extending from said side members serving as furnace bearer seats, and means for securing the 30 castings together.

13. In a locomotive the combination of a pair of cylinders having pistons; a pair of main drive wheels; main drive rods connecting the pistons and the main drive wheels; a pair of drive wheels in advance of the main drive wheels; and a sectional bed comprising, as one of the sections an integral casting 40 extending forwardly from a point at the rear of the main drive wheel axle to a point forward of the cylinders, having side frame members of substantially channel-shaped cross-section united by a substantially continuous transverse web, each of said side frame members having a pedestal jaw opposite each of the adjacent drive wheels, a separate section comprising the remainder of the bed, and means for securing the casting and the remainder of the bed together.

14. In a locomotive the combination of a pair of cylinders having pistons; a pair of main drive wheels; main drive rods connecting the pistons and the main drive wheels; a pair of drive wheels in advance of the main drive wheels; and a sectional bed comprising, as one of the sections an integral casting 50 extending forwardly from a point at the rear of the main drive wheel axle to a point forward of the cylinders, having side members of substantially channel-shaped cross-section formed with pedestal jaws opposite adjacent 55

drive wheels and longitudinal braces, and a substantially continuous web connecting the side members, apertured for spring hangers and spring saddles, a separate section comprising the remainder of the bed, and means 70 for securing the casting and the remainder of the bed together.

15. A boiler-supporting sectional frame having a plurality of pairs of pedestals for journal boxes, comprising a frame section including a part having the pedestals for the journals of the main drive, and a part in advance thereof, formed as an integral casting; vertical flanged joint means formed 75 integral therewith and to the rear of said pedestals; an adjacent frame portion to the rear of said section having vertical joint means; and means, including a key, for rigidly securing the joint means together.

16. A boiler-supporting sectional frame having a plurality of pedestals for journal boxes, comprising a frame section including a part having the pedestals for the journals of the main drive, and a part in advance thereof, formed as an integral casting; an adjacent portion to the rear of said section, including side members having pedestals for journal boxes; a cradle member to the rear of said adjacent portion, having a draw bar pocket, formed as an integral casting; means 80 for rigidly securing the integral section and adjacent portion together; and means for rigidly securing the cradle portion to the adjacent portion.

17. A boiler-supporting sectional frame having a plurality of pairs of pedestals for journal boxes, comprising a frame section including a part having the pedestals for the journals of the main drive, and a part in advance thereof, including a seat for the reception of combined cylinders and boiler saddle, formed as an integral casting; an adjacent frame portion to the rear of said section; and means for rigidly securing the integral section and adjacent portion together. 105
